UNITED STATES PATENT OFFICE

166,768

MEDAL OR SIMILAR ARTICLE

Virginia O. Metsker, Wichita, Kans.

Application June 13, 1951, Serial No. 15,525

Term of patent 14 years

(Cl. D29—19)

To all whom it may concern:

Be it known that I, Virginia O. Metsker, a citizen of the United States, residing at Wichita, county of Sedgwick, State of Kansas, have invented a new, original, and ornamental Design for a Medal or Similar Article, of which the following is a specification, reference being had to the accompanying drawing, forming a part hereof.

Fig. 1 is a front view of a medal or similar article, showing my new design.

Fig. 2 is a back view of same.

Fig. 3 is a sectional view of same, taken along line 3—3 of Fig. 1.

The characteristic features of my design reside in those portions shown in full lines.

I claim:

The ornamental design for a medal or similar article, as shown and described.

VIRGINIA O. METSKER.
